(57) **CLAIM**

The ornamental design for a safety seat, as shown and described.

DESCRIPTION

FIG. 1 is a front, right, and top perspective view of a safety seat, of our new design;

FIG. 2 is a front elevation view of thereof;

FIG. 3 is a rear elevation view thereof;

FIG. 4 is a left side view thereof;

FIG. 5 is a right side view thereof;

FIG. 6 is a top view thereof;

FIG. 7 is a bottom view thereof; and,

FIG. 8 is another front, right, and top perspective view of the safety seat shown in FIG. 1, illustrating a seat rotated at an angle to the right from a position shown in FIG. 1.

The broken (dashed) lines show portions of the safety seat that form no part of the claimed design.

1 Claim, 8 Drawing Sheets
